SURFACE ORNAMENTATION OF WALLS, &c.

No. 16,242.

Fig. 1. Patented Sept. 8, 1885.

Fig. 2.

UNITED STATES PATENT OFFICE.

FREDERICK MANKEY, OF WILLIAMSPORT, PENNSYLVANIA,

DESIGN FOR SURFACE ORNAMENTATION OF WALLS, &c.

SPECIFICATION forming part of Design No. 16,242, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification, reference being had to the accompanying photographs, forming part hereof.

Figure 1 is a plan view of a panel on which is formed my new design. A variation of said design is shown in Fig. 2.

Similar letters of reference indicate like parts.

My design consists of a series of elevations, A and B, placed alternately in rows extending longitudinally the panel. The elevations A have a quadrangular base portion and a prismatic upper portion, as represented. The elevations B have a quadrangular base portion and a pyramidal upper portion. Between each of the elevations A and B is a transverse channel, D, of rectangular cross-section, and between the longitudinal rows of elevations there is a longitudinal channel, E, of like section. In Fig. 1 the elevations A in row 1 alternate with the elevations B in row 2. In Fig. 2 the elevations A in row 1 correspond to the elevations A in row 2. I may arrange the design on the panel in either of the ways represented.

I claim—

1. The design for a surface ornamentation of walls, &c., herein shown and described, the same consisting of elevations A and B, each elevation A having a quadrangular base portion and a prismatic upper portion, and each elevation B having a quadrangular base portion and pyramidal upper portions, the said elevations A and B being alternately placed in rows longitudinally the surface, and separated by channels E and D, of rectangular cross-section. 35

2. The design for a surface ornamentation of walls, &c., herein shown and described, the same consisting of elevations A and B, each elevation A having a quadrangular base portion and a prismatic upper portion, and each elevation B having a quadrangular base portion and a pyramidal upper portion, the said elevations A and B being placed alternately 40 in a row longitudinally the surface, and separated by channels D, of rectangular cross-section. 45

FREDERICK MANKEY.
